United States Patent [19]

Chang et al.

[11] Patent Number: Des. 308,722

[45] Date of Patent: ** Jun. 19, 1990

[54] IMMUNOASSAY MATRIX

[75] Inventors: Tse W. Chang; Nancy T. Chang, both of Houston, Tex.

[73] Assignee: Tanox Biosystems, Inc., Houston, Tex.

[**] Term: 14 Years

[21] Appl. No.: 39,652

[22] Filed: Apr. 17, 1987

[52] U.S. Cl. D24/8

[57] CLAIM

The ornamental design for an immunoassay matrix, as shown and described.

DESCRIPTION

FIG. 1 is a perspective view of an immunoassay matrix showing our new design;

FIG. 2 is a top plan view thereof, the bottom plan view being the same in appearance;

FIG. 3 is an end elevational view thereof;

FIG. 4 is a side elevational view thereof;

FIG. 5 is a second embodiment of FIG. 1, the undisclosed portions being identical to that shown in FIGS. 2-4 and the only difference residing in the number of clear circles disclosed;

FIG. 6 is a third embodiment of FIG. 1, the undisclosed portions being identical to that shown in FIGS. 2-4 and the only difference residing in the number of clear circles disclosed.
